UNITED STATES PATENT OFFICE.

HENRY P. MERRIAM, OF NEW YORK, N. Y.

FUSE FOR PROJECTILES.

SPECIFICATION forming part of Letters Patent No. 630,621, dated August 8, 1899.

Application filed October 26, 1898. Serial No. 694,587. (No model.)

To all whom it may concern:

Be it known that I, HENRY P. MERRIAM, a citizen of the United States, residing at New York, in the county and State of New York, have invented certain new and useful Improvements in Fuses for Projectiles, of which the following is a specification.

My invention relates to improvements in percussion-fuses for projectiles, my object being to simplify and improve the structure and operation of such fuses to insure greater safety in handling the projectiles and certainty in exploding the shell after it strikes the target.

15 To these ends my invention consists, broadly, of a fuse-body adapted to be secured in the base of a projectile and formed with a hammer-chamber and a bolt cavity or socket, a hammer supported in the chamber and having a securing pin or shank connected with and projecting from it through a suitable opening into the bolt socket or cavity transversely of the path of movement of the bolt and constructed and arranged to yield and 20 break under a transverse bending strain, and a bolt supported in the bolt cavity or socket and exposed to the gas-pressure of the propelling charge of the gun, to be forced thereby against the securing-pin to bend the pin laterally and break off the head from the pin to release the hammer in its chamber. 25 Normally the hammer is supported in inoperative position in one end of its chamber by the securing-pin, which is suitably held in the bolt cavity or socket. The hammer end of the securing-pin is held against substantial lateral movement, while the end of the pin in the bolt cavity or socket is exposed to the transverse bending strain exerted upon 30 it by the bolt when the latter is forced forward in its cavity by the gas-pressure of the propelling charge of the gun, the securing-pin being thereby bent until it breaks adjacent to the hammer. With such a structure, 35 whereby the pin is broken by a transverse bending strain, it is possible to use, with a given force exerted upon the bolt, a much stronger securing-pin than would be possible if the release of the hammer depended upon 40 the shearing off of the pin by the bolt. My improved structure of fuses therefore affords greater safety in handling projectiles and in-

sures certainty in releasing the hammer upon discharge of projectile from gun.

More specifically the invention, as illustrated in the accompanying drawings and hereinafter particularly described, comprises a hammer supported in the hammer-chamber of the fuse-body and having a headed securing-pin attached to it and extending through a suitable opening into the bolt cavity or socket, the hammer being supported in inoperative position in one end of its chamber by the engagement of the pin-head with the wall of the bolt cavity or socket, and a bolt supported freely in the bolt socket or cavity in engagement with the head of the securing-pin and exposed at its outer end to the gas-pressure of the propelling charge of the gun, to be forced thereby against the securing-pin 65 head for bending the pin laterally and breaking off the head from the pin to release the hammer in its chamber.

In the forms of fuse shown in the drawings the hammer-securing head which rests in the bolt cavity or socket is preferably spherical, and the bolt is unattached to the head, but rests against the head, so that when the bolt is forced forward in its cavity or socket by the firing of the gun charge the spherical 75 head will be forced along the bolt-cavity in front of the bolt and transversely of the length of the pin or shank which secures the head to the hammer, so as to break the head from the pin and release the hammer in its 80 chamber. The rounded or spherical shape of the securing-head is important, as it affords an effective leverage for breaking off the head by the movement of the bolt.

The fuse-body is preferably provided with 90 a circular opening leading from the hammer-chamber to the bolt-socket for the passage of the hammer-securing head into the bolt-socket, and a notch in the inner wall of said circular opening arranged in the central longitudinal 95 axis of the fuse-body to receive the pin or shank of the securing-head, the head being held in position to support the hammer by the engagement of the bolt or a removable tubular plug. When the bolt holds the securing-pin in place, means must also be provided for confining the bolt in its socket.

In the preferred construction of the fuse embodying my invention the inner end of the

5 fuse-body is threaded to receive an annular head formed with a conical or dished inner face in which is seated a radial series of firing-pins and primers, the primers being in communication with a common combustion or 10 firing chamber in which is supported a slow-burning or delay charge, and the annular fuse-head is closed by a hollow plug or cap containing a quick-burning igniting charge, 15 which is confined in the plug or cap by a disk or diaphragm secured in place by upsetting the metal of the plug or cap upon the disk or diaphragm. The chamber of the plug or cap has a central opening communicating with the 20 combustion or firing chamber, through which the flash from the slow-burning charge communicates with the quick-burning igniting charge. The explosion of the quick-burning charge ignites the bursting charge of the shell, 25 the disk or diaphragm being perforated to allow the flame to communicate with the bursting charge or adapted to be blown from its seat for this purpose.

30 In order that my invention may be fully understood, I will first describe the same with reference to the accompanying drawings and afterward point out the novelty with more particularity in the annexed claims.

35 In said drawings, Figure 1 is a sectional view of a portion of a shell representing my improved fuse applied thereto, the parts being in the position they assume before the shell is fired. Fig. 2 is a sectional view of the fuse, showing the hammer liberated and in the position assumed, when detonating the primers, at the instant the velocity of the shell is suddenly checked, as when striking a target. Fig. 3 is a detail view showing the arrangement of the plurality of the primers or fulminates and their firing-pins. Fig. 4 is a detail plan view of the fuse-body, the primer head or carrier and the hammer being removed to show the peculiar shape of opening 40 leading from the hammer-chamber to the bolt socket or cavity. Fig. 5 is a detail plan view of the delay-valve containing the slow-burning or delay charge of explosive. Fig. 6 is a detail plan view of the cap containing the quick-burning charge, showing a slight modification. Fig. 7 is a detail longitudinal sectional view of a modified form of my fuse.

45 In the base of the shell 1 is formed an interiorly-threaded opening into which the body 2 of my improved fuse is screwed. The fuse-body 2 is formed with a hammer-chamber 3, having a hemispherical lower portion 3^a, in which the spherical hammer 4 normally rests. The hammer 4 is provided with a spherical retaining-head 5, attached to it by a reduced 50 shank or pin 6. The hammer 4, head 5, and shank or pin 6 are preferably turned out in an integral piece, but the head and shank may be separately formed and secured to the hammer in any suitable manner.

55 7 is the bolt cavity or socket, formed in and extending transversely of the body of the fuse and open at one end to expose the firing bolt

or piston to the pressure of the gases of the propelling charge of the gun.

80 8 is an inclined circular opening leading 70 from the lower portion 3^a of hammer-chamber 3 into the bolt-cavity 7, and 8^a is a semi-circular notch formed in the inner wall of opening 8, the notch 8^a being in the central longitudinal line of the fuse-body and 75 the enlarged opening or passage 8 being to one side of said central line, and the opening 8 and notch 8^a forming a locking-eyelet for the hammer-retaining head 5, as hereinafter explained.

85 9 is a cylindrical bolt or piston resting freely in the bolt socket or cavity 7 and confined against the head 5 by means of a pin 10, passing transversely across the outer end of socket 7 and seated in the walls of the socket. 90 In locking the hammer 4 in place the head 5 is passed through opening 8 into bolt-cavity 7, and the hammer 4 is rotated slightly in its seat 3^a to bring the pin 6 into the notch 8^a and the head 5 in the bolt-socket. The bolt 90 is then slipped into its socket against head 5 and secured by pin 10. The bolt or piston 9 has its outer end bored out slightly to form an annular flange 9^a, which can be expanded into close contact with wall of bolt socket or 95 cavity 7 to prevent the passage of powder-gases past the bolt 9 into the hammer-chamber. If preferred, the usual soft-metal gasket or thimble (not shown) may be employed to prevent the passage of powder-gases. The 100 bolt or piston 9 is of sufficient length to shut off communication between opening 8 and open end of socket 7 whether the bolt is in its normal outer position or its inner position, which is assumed after firing.

105 In Fig. 7 I have illustrated a modified form of the above-described hammer securing and releasing device. In this form of the device the hammer and retaining pin and head are the same as in the preferred form shown in 110 Figs. 1 and 2. The bolt cavity or socket 7^a is, however, bored through from side to side of the fuse-body and is reamed out to a larger diameter for one-half of its length to receive a tubular plug 12, having a solid threaded 115 head 12^a, which is threaded into the enlarged bore of the bolt-cavity. The bore of the tubular plug 12 is of the same diameter as the bolt socket or cavity 7^a, forming a continuation 120 thereof for the purpose hereinafter explained. The locking-eyelet 8 8^a, communicating between the hammer-chamber 3 and bolt-cavity 7^a, is in this modified form of the device arranged to communicate with the enlarged bore of the bolt-cavity farthest away 125 from the open end thereof, so that when the hammer-retaining head 5 is passed through opening 8 into the bolt-cavity and the tubular plug 12 is put in place the inner edge of the plug will engage the pin 6 and hold it 130 snugly in place in the notch 8^a, the head 5 engaging the inner wall of the bolt-cavity and inner wall of the plug for firmly supporting the hammer in its seat 3^a.

The inner end of the fuse-body 2 is internally threaded for the reception of the annular head or primer-carrier 20, which is formed with a series of passages 21, leading from the 5 hammer-chamber 3 to a combustion-chamber 22, and a series of sockets 23, in which are mounted the primers or fulminate-patches 24, which rest against the firing-lugs 25. 26 are ball-firing pins, also secured in the sockets 23 10 in contact with the primers 24.

27 are openings leading from the primers to the combustion-chamber 22.

30 is a cylindrical controller or delay valve, formed with a central stem 31, which rests in 15 the central cylindrical socket 32, formed in the head 20. The valve 30 rests normally upon the central annular flange 20^a of the head 20. The controller-valve 30 has radial cuts or notches 30^a, and packed tightly within 20 the recess in the face of the valve and in the cuts or notches 30^a is the delay-burning charge 35, of any suitable material. It will be observed that the radial cuts or notches 30^a expose small parts of the tightly-packed charge 25 35 at the edge of the valve within the combustion-chamber 22.

40 is a hollow plug or cap threaded into the upper end of the head 20, the plug or cap 40 having a chamber 40^a, within which is packed 30 the quick-burning charge 41. The chamber 40^a has a central opening 40^b, which forms a communication between the combustion-chamber 22 and the quick-burning charge 41.

In Fig. 1, 41^a is a dished disk of very thin 35 celluloid placed in cap 40 beneath the charge 41 to prevent the loosely-packed charge sift- 40 ing through opening 40^b into the combustion-chamber 22. The flash from the delay charge 35 readily pierces the celluloid 41^a for ignit- 45 ing charge 41.

In Fig. 2 I have shown a wad of guncotton 41^b, serving the same purpose as disk 41^a of celluloid. The chamber 40^a is closed by a disk 43, which rests upon a flange or shoulder in 45 the chamber and is secured by upsetting the surrounding metal of the plug or cap 40 upon the disk. The upset portion is indicated at 44. The disk 43 is blown off by the charge 41 to fire the shell-bursting charge. As shown 50 in Fig. 6, the disk 43 may be formed with a number of perforations 43^a, to allow the flash of charge 41 to pass into the bursting charge of the shell without necessarily blowing off the disk 43.

55 The inner face of the head 20 is dished or formed with a conical socket, in which the ball-receiving openings 23 are formed. In the center of the conical socket is formed a cylindrical recess in which rests a small con- 60 ical spring 50, which is adapted to engage the hammer 4 for steadyng it and preventing its knocking against its casing during flight. When the velocity of the shell after firing is retarded, as when striking a target, the spring 65 50 is easily compressed by the hammer and does not appreciably interfere with the detonation of the primers.

The parts of my improved fuse are assembled as follows: The hammer 4 and the attached pin 6 and head 5 are placed in the 70 hammer-chamber 3 of the fuse-body and inclined slightly, and in this position the head 5 is passed through opening 8. The hammer and attached parts are then rotated slightly, the hammer moving in its seat 3^a to bring 75 head 5 in proper position in bolt-socket 7 and pin 6 in the notch 8^a. The bolt 9 is then placed in its socket against the head 5, and the pin 10 or other equivalent device is secured in place. The bolt 9 holds the head in 80 position and prevents its sidewise movement toward opening 8, the head engaging the wall of the socket to support the hammer 4 in its seat 3^a. The hammer end of the securing-pin is held against lateral movement, while 85 the headed end of the securing-pin in the bolt cavity or socket is in position to be exposed to a transverse strain exerted upon it by the bolt when the latter is forced forward in its cavity by the gas-pressure of the pro- 90 pelling charge of the gun. This transverse strain upon the securing-pin breaks it to free the hammer. The head 20, with its attached parts, is screwed in place in the fuse-body, when the fuse is ready to be applied to the 95 shell.

In the modified form shown in Fig. 7 the tubular plug being removed the hammer 3 is put in place in the fuse-body, with the head 5 in the bolt-socket, as above explained, and 100 the tubular plug is then screwed into position in the enlarged and threaded end of the bolt-socket, engaging the pin 6 of the head 5 to hold the parts in position. In this form of the device the bolt 9 rests against the head 5 105 on the opposite side of plug 12 and need not be secured as in the preferred form.

The fuse being applied to the projectile with the parts as shown in Fig. 1 the projectile is fired from the gun. The pressure of the exploded propelling charge of the gun which expels the projectile forces the bolt or piston 9 longitudinally in its socket or cavity 7, the inner end of the bolt or piston engaging the spherical head 5 of the hammer-retaining pin 6 and forcing it along the socket or cavity 7, straining and bending the pin 6 laterally, causing it to break and freeing the hammer 4, as shown in Fig. 2. The engagement of the plane surface of the inner end of 110 the bolt or piston 9 with the curved face of the spherical head 5 affords ample leverage for readily breaking the pin 6, the head tending to roll against the surface of socket 7 to assist in the breaking action. During the 115 flight of the projectile the hammer 4 rests under the force of spring 50 in the hemispherical recess 3^a of the hammer-chamber and the controller-valve 30, carrying the slow-burning charge 35, rests against the central 120 annular flange 20^a of the combustion-head 20, as shown in Fig. 1. As soon as the projectile strikes the target its velocity will be 125 suddenly checked, and the hammer 4 will be 130

forced to the inner end of its chamber, compressing spring 50 and striking one or more of the firing-pin balls 23, and the valve 30 will be forced against the inner face of the 5 cap or plug 40.

The percussion of hammer 4 against one or more of the firing-pin balls 23 detonates one or more of the primers 24, and the flash from the primers passes into the combustion-chamber 22 and ignites the delay charge 35 at the edges, the surface of the delay charge 35 being entirely covered by cap 40, and only the small portions of said charge in the cuts or notches 30^a being exposed. The delay charge 15 35 gives the shell time to pierce the target. During the penetration of the target the valve 30 is firmly held against cap 40 by reason of the violent checking of the velocity, but immediately after the retardation of the shell 20 has ceased the pressure of the gas generated between the surfaces by the delay charge forces the valve back against the annular seat 20^a. As soon as the valve 30 is returned to seat 20^a the fire reaches over the unburned 25 delay charge and passes to the center of the quick-burning charge 41, piercing the celluloid 41^a or igniting the guncotton 41^b and exploding the charge 41, blowing out the disk 43 (or flashing through perforations 43^a) and 30 igniting the bursting charge of the projectile.

The operation of the modified form shown in Fig. 7 is practically the same as the preferred form. The bolt 9, engaging head 5, breaks the head from the pin 6, the pin being 35 supported by the engagement of the tubular plug 12 and the head being forced into the bore of the plug.

It will be observed that in both the preferred and modified forms of the fuse the 40 locking eyelet or opening which communicates between the hammer-chamber and bolt cavity or socket comprises an enlarged hole or opening 8, extending through the bottom of seat 3^a at one side of the central longitudinal line of the fuse-body, and a contracted portion or notch 8, extending through the bottom of seat 3^a in the central longitudinal line of the fuse-body. The enlarged portion of the eyelet or opening permits the passage 45 of the round hammer-retaining head into the bolt-cavity, and the contracted portion or notch receives the pin or shank of the head. In both forms means must be provided for holding the head against accidental sidewise 50 movement toward the enlarged part 8 of the eyelet or opening. In the preferred form of the device the bolt 9 holds the head in locked position, while in the modified form the tubular plug holds the head in position.

60 The principal useful and desirable result derived from my improved arrangement is the greatest possible safety with a given force available for releasing the hammer, whereby the hammer can be more effectively secured 65 against accidental release previous to the firing of the shell. It is evident that the limitation of the force holding the hammer in

its seat in the fuse-body is the direct tensile strength of the smallest cross-section of the retaining pin or shank, and the strain, set up 70 by accidental shocks to which the fuse is subjected previous to firing, which would tend to release the hammer in its chamber would almost entirely be that of direct tension upon the pin or shank, while the force necessary to 75 the release of the hammer in its chamber is a transverse bending force controllable by a sharp groove or thread cut in a single short section of the pin or shank. The disparity between these two forces can be readily shown by 80 taking a small metal rod, preferably steel, having a sharp circumferential groove cut into it at a point midway of its length. To break this grooved rod by a transverse bending strain concentrated at the reduced section 85 would require only a small fraction of the force necessary to disrupt the rod by direct tension or shearing.

By the expression used in the specification and claims "the securing pin or shank connected with the hammer" I mean to cover any and all means of connecting or joining the securing pin or shank and hammer whether the pin or shank is screwed into the hammer or is formed integral with the hammer or 95 passes loosely through the hammer and confines the hammer upon it by means of a head or enlargement or other confining means or any other connection whereby the hammer is supported in its chamber by the pin or shank. 100

I wish it to be understood that my invention is broadly distinguishable from those fuses in which the hammer is released by directly shearing or cutting off its securing-pin between the coacting surfaces of the bolt and 105 wall of the bolt-cavity in that in my invention the securing-pin is subjected to a transverse bending strain by the forward movement of the bolt to break the pin and release the hammer. I believe I am the first to break 110 the securing-pin by a bending strain to release the hammer as distinguished from shearing or cutting off the pin to release the hammer.

Having thus described my invention, what 115 I claim as new, and desire to secure by Letters Patent, is—

1. In a percussion-fuse for projectiles, the combination of a fuse-body having a hammer-chamber and a bolt socket or cavity, a hammer in said chamber having a securing-pin attached to it and extending into and held within said bolt cavity or socket to support the hammer, said securing-pin being constructed and arranged to yield and break under transverse bending strain, and a bolt or piston supported in said bolt cavity or socket so as to be exposed to the gas-pressure of the propelling charge of the gun and adapted to be forced forwardly in its socket thereby, to strain the securing-pin laterally and bend and break the same for releasing the hammer in its chamber, substantially as set forth. 125

2. In a percussion-fuse for projectiles, the

combination of a fuse-body having a hammer-chamber and a bolt socket or cavity, a hammer in said chamber having a securing-pin attached to it and extending into and held 5 within said bolt cavity or socket to support the hammer, said securing-pin being held at the hammer end against substantial lateral movement while its other end is capable of lateral movement to effect the bending and 10 breaking of the pin, and a bolt or piston supported in said bolt cavity or socket so as to be exposed to the gas-pressure of the propelling charge of the gun and adapted to be forced forwardly in its socket thereby, to 15 strain the securing-pin laterally and bend and break the same for releasing the hammer in its chamber, substantially as set forth.

3. A percussion-fuse for projectiles comprising a fuse-body having a hammer-chamber and a bolt cavity or socket, a hammer having a securing-head attached to it and resting in the bolt cavity or socket, said head engaging the wall of the bolt cavity or socket and supporting the hammer in inoperative 25 position in its chamber, and a bolt or piston freely supported in the bolt cavity or socket in position to be exposed to the gas-pressure of the propelling charge of the gun, and adapted to be forced thereby against the securing-head to break the head from the hammer and free the hammer in its chamber, substantially as and for the purpose set forth.

4. A percussion-fuse for projectiles comprising a fuse-body having a hammer-chamber and a bolt socket or cavity, a hammer in the chamber, a pin secured to the hammer passing through an opening between the hammer-chamber and bolt cavity or socket and provided with rounded head which rests in 35 the bolt cavity or socket and by its engagement therewith supports the hammer in its chamber, and a bolt or piston supported in the bolt cavity or socket in position to be exposed to the pressure of gas of the propelling 40 charge of the gun and adapted to be forced

against the rounded head for breaking the pin and releasing the hammer, substantially as set forth.

5. A percussion-fuse for projectiles comprising a fuse-body having a hammer-chamber and a bolt cavity or socket communicating with the hammer-chamber through a locking eyelet or opening having an enlarged part and a contracted part or notch, a hammer in the hammer-chamber, a rounded head having 55 its pin or shank secured to the hammer, the head being adapted to be passed through the enlarged part of the locking-eyelet into the bolt cavity or socket and the pin or shank to engage in the contracted part or notch of the 60 eyelet, and a bolt or piston freely supported in the bolt cavity or socket in position to be exposed to the gas-pressure of the propelling charge of the gun and adapted to engage the rounded head and force it to one side to 65 break the pin and release the hammer, substantially as set forth.

6. A percussion-fuse for projectiles comprising a fuse-body having a hammer-chamber and a bolt cavity or socket communicating with the hammer-chamber through a locking eyelet or opening having an enlarged part and a contracted part or notch, a hammer in the hammer-chamber, a rounded head having 70 its pin or shank secured to the hammer, the head being adapted to be passed through the enlarged part of the locking-eyelet into the bolt cavity or socket and the pin or shank to engage in the contracted part or notch of the 75 eyelet, a bolt or piston supported in the 80 bolt cavity or socket in engagement with the rounded head and exposed to the gas-pressure of the propelling charge of the gun, and a device retaining the bolt in its socket, substantially as set forth.
